Primary Examiner — Angela J Lee*Assistant Examiner* — Shawn T Gingrich(74) *Attorney, Agent, or Firm* — K&L Gates LLP(57) **CLAIM**

The ornamental design for a digital motor protection relay, as shown and described.

DESCRIPTION

FIG. 1 is a perspective view of a digital motor protection relay showing the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a perspective view thereof in a use condition.

The broken lines shown in the drawings illustrate portions of the digital motor protection relay that form no part of the claimed design.

1 Claim, 6 Drawing Sheets(56)
